UNITED STATES PATENT OFFICE.

EWALD G. BAUM, OF NATICK, MASSACHUSETTS, ASSIGNOR TO SEAL-KAP COMPANY, OF NATICK, MASSACHUSETTS, A CORPORATION OF MASSACHUSETTS.

BOTTLE CAP.

Application filed March 21, 1924. Serial No. 700,836.

This invention relates to bottle caps more especially those designed to close off the mouths of milk bottles and has for its chief object to provide a construction whereby the 5 cap may be closed into tight sealing engagement with the bottle regardless of very considerable variations in the contour of those portions of the bottle with which the cap is intended to cooperate.

10 While not restricted thereto, it is particularly applicable to two-part caps of the general type illustrated in my application for patent, Serial No. 616,874, filed February 5, 1923, for milk bottle caps, embodying one 15 part having a pouring lip housing and a bore covering portion joined thereto by an annular bottle engaging portion, and another part comprising a disk overlying the bore covering portion of the first part with 20 its periphery in engagement with the inner wall of the pouring lip housing.

Referring to the accompanying drawings, Figure 1 is a plan of the cap. Figure 2 is an inverted plan of the same. 25 Figure 3 is a section on line 3—3 of Figure 2.

Figure 4 is a fragmentary section through the upper portion of a bottle having a cap applied thereto.

30 Figures 5, 6 and 7 are views similar to Figure 4, but showing the cap applied to bottles having their portions with which the cap seals of different contours.

The cap comprises two parts, one having 35 an annular pouring lip housing portion 1 which is shown as corrugated over the upper edge of the bottle mouth. Immediately within this pouring lip housing is a downwardly inclined or frusto conical portion 2 which is arranged to be seated on and to conform to the edge of the annular ledge 3 with which such bottles are provided below their open ends and on which the commonly used cardboard closure disks are intended to be seated. Inwardly of the portion 2 is a bore covering portion comprising 40 a substantially flat central disk surrounded by a downwardly and outwardly inclined annular portion 6. In order to stiffen this 45 cap so that it holds firmly in position a disk 8 is forced downwardly within the pouring lip housing portion, its periphery resting against and forcing outwardly the inner wall of this portion so that when the 50 cap is applied to the bottle it firmly engages the bottle pouring lip when it flares downwardly and outwardly above the ledge 3. The disk portion 8, together with the portions 2 and 6 of the other cap part, form an annular portion of substantially triangular cross section immediately within and below the pouring lip housing. When the cap is applied this portion 2 is conformed to the mating bottle portion and serves as a sealing gasket. The moistening of this 55 portion by the milk tends to soften and swell the paper-board of which the cap is preferably made, so that this sealing gasket action is augmented.

The portion 2 is of considerable width so 60 that it may engage and be conformed to the ledge 3 of the bottle regardless of very considerable variations in the contour of this ledge or departures from a truly circular outline. For example, as shown in Figure 4, the ledge 65 3 is considerably rounded merging somewhat gradually with the inner wall of the bottle 4 immediately therebelow, while in Figure 5 the edge between the ledge 3 and the inner wall 4 of the bottle is sharply defined and inclines upwardly. In Figure 6 the ledge is formed substantially flat on its 70 upper face and with its inner edge comparatively sharp, while in Figure 7 it is sloped downwardly at a very considerable angle. 75 Regardless of these variations in contour, however, the annular portion 2 may be made to conform thereto as the cap is forced into proper seating engagement with the bottle mouth. Not only does this construction 80 take account of variations in the cross sectional contour of the ledge, but also provides for departures from true circular form. For example, in Figure 2 is shown in dotted lines at 10 the line of engagement with the 85 portion 2 of the cap of the inner edge of the ledge when this inner edge is elliptical rather than circular, it being noted that it engages near the outer edge of the portion 2 at oppositely disposed points *a* and *b* and near the inner edge at points *c* and *d* midway between. Of course any other variations or irregularities, so long as the edge of the ledge strikes between the inner and outer margins 90 of the portion 2 are effectually taken care of so that the bottle will be fully sealed when the cap is applied thereto.

The triangular cross section, hereinbefore mentioned, of which the portion 2 forms one 95 side furnishes a substantial stiffness to the 100

105

110

cap which acts to hold the portion 2 into close contact with the mating portions of the bottle in whatever manner the portion 2 must be deformed in the process. Thus a 5 very tight sealing engagement may be produced between the cap and the bottle while requiring nothing more than a commercial degree of accuracy of either the bottle or the cap.

10 Having thus described an embodiment of this invention it should be evident that various modifications and changes might be made therein without departing from its spirit or scope as defined by the appended 15 claims.

I claim:

1. A bottle cap having a bore covering portion terminating in an upwardly inclined annular portion to engage and be 20 closely conformed to the usual internal annular ledge adjacent to the mouth of a milk bottle and extended downwardly beyond the face of the ledge to form a sealing contact beneath it and serve as a sealing gasket 25 therefor.

2. A bottle cap having a bore covering portion terminating in an upwardly inclined annular portion to engage and be closely conformed to the usual internal 30 annular ledge adjacent to the mouth of a milk bottle and extended downwardly beyond the

face of the ledge to form a sealing contact beneath it, said annular portion being of sufficient width to be conformable to bottles of different internal contours and irregularities and serve as a sealing gasket therefor. 35

3. A bottle cap comprising a bore covering portion having a marginal portion of triangular section having one face upwardly and outwardly inclined and deformable 40 to conform to the inner wall of a milk bottle at and below the usual internal disk supporting ledge.

4. A bottle cap comprising a bore covering portion having a marginal portion of 45 triangular section having one face upwardly and outwardly inclined and deformable to conform to the inner wall of a milk bottle at and below the usual internal disk supporting ledge, said face being of substantial 50 width to conform to ledge portions of different contours and irregularities.

5. A bottle cap having a bore covering portion, a pouring lip housing, and an annular frusto conical portion between said 55 bore covering portion and lip housing engageable with and conformable to the inner face of a bottle at and below an internal annular ledge adjacent to its mouth.

In testimony whereof I have affixed my 60 signature.

EWALD G. BAUM.
